UNITED STATES PATENT OFFICE.

ISAAC SNOW, OF LAWRENCE, MASSACHUSETTS, ASSIGNOR, BY MESNE ASSIGNMENTS, TO DRAPER CORPORATION, OF HOPEDALE, MASSACHUSETTS, A CORPORATION OF MAINE.

SHUTTLE-FEELER FOR LOOMS.

1,230,439.

Specification of Letters Patent. Patented June 19, 1917.

Application filed April 25, 1916. Serial No. 93,533.

To all whom it may concern:

Be it known that I, ISAAC SNOW, a citizen of the United States, and resident of Lawrence, county of Essex, State of Massachusetts, have invented an Improvement in 5 Shuttle-Feelers for Looms, of which the following description, in connection with the accompanying drawing, is a specification, like characters on the drawing representing 10 like parts.

This invention relates to improvements in shuttle feelers and the principal object of the invention is to provide a shuttle feeler which will be of greater efficiency in operation 15 than those heretofore constructed and which will avoid wearing or otherwise damaging the shuttle or the shuttle engaging portion of the feeler.

In the operation of the shuttle feelers as 20 heretofore constructed the end of the feeler is advanced to feeling position upon call for transfer and if the shuttle is improperly positioned therein engages the side or end portion of the shuttle so that as the lay beats 25 forward the shuttle feeler is actuated to withdraw the latch on the transfer arm from operative relation to the bunter upon the lay, thus preventing transfer and the consequent smashes which otherwise would 30 result from the actuation of the transfer mechanism with an improperly positioned shuttle.

When the end of the feeler or the shuttle becomes worn the feeler sometimes is not sufficiently actuated by an improperly positioned 35 shuttle to throw the dog out of the path of the bunter on the lay so that as the latter moves forward the transfer arm is actuated and a smash occurs.

The present invention is designed to avoid 40 damage to the shuttle and to the feeler, thus prolonging the life of these instrumentalities and also insuring the effectiveness of the operation of the feeler.

The objections above mentioned are obviated 45 in the preferred embodiment of the invention illustrated herein by providing a shuttle feeler with a relatively movable shuttle engaging instrumentality adapted upon contact with an improperly positioned 50 shuttle to position the latch in the path of the lay so that as the lay beats forward the shuttle feeler will be thrust forward by the direct action of the lay upon the latch, the only pressure placed upon the shuttle engaging 55 instrumentality of the feeler being

that which is required to position the latch in the path of the lay. This construction entirely obviates the wear upon the shuttle and the shuttle engaging end of the feeler heretofore caused, wherein all of the power required to actuate the shuttle feeler is transmitted through the portion of the shuttle which engages the end of the feeler. 60

By this construction the more effective operation of the shuttle feeler is obtained, 65 since the shuttle engaging end of the feeler yields readily and does not have a tendency to thrust the shuttle back into its box in such a manner as to improperly position it in relation to the transferring mechanism. 70

Other objects of the invention will more fully appear from the following description, the accompanying drawings, and will be pointed out in the annexed claims. 75

In the drawings;

Figure 1 is a sectional view showing a sufficient portion of a loom to illustrate my invention embodied therein,

Fig. 2 is a detail view of the end of the shuttle feeler with my invention applied 80 thereto,

Fig. 3 is a similar detail view illustrating a shuttle feeler embodying my invention engaging the shuttle and positioning the latch in the path of the lay. 85

Fig. 4 is a plan view of the end of the shuttle feeler embodying the constructions illustrated in Figs. 2 and 3, and

Fig. 5 is a detail view of a feeler equipped with a different mechanism embodying my 90 invention.

The structure illustrated in the accompanying drawings comprises the usual frame 1, the breast beam 2, a hopper 3 having the usual pivotally mounted transferring arm 4, 95 the lower end of said arm being connected to a dog 5 adapted to coöperate with the bunter 6 upon the lay 7 which is supported upon the sword 8. The mechanism for controlling the action of the transfer arm may 100 be and is of the character usual in automatic filling replenishing looms of the Northrop type the actuation of the transfer arm being controlled through the controller rod 9 journaled in the bracket 10 carried by the frame 105 or breast beam. The controller rod 9 is provided with an arm 11 which engages a stud 12 upon an extension 13 of a shuttle feeler 14 which is pivoted upon a stud 15 carried by a bracket 17 projecting from the loom 110

frame. A spring 16 upon said stud normally tends to rock the shuttle feeler 14 so as to advance its end to feeling position but such action is normally restrained by the arm 11 which bears upon the stud 12 and is under the influence of the spring 11^a.

As shown herein the shuttle feeler is of the usual U-shaped construction and provided with a member 18 which is mounted upon the stud 19 and having a slot 20 engaging a stud 21 upon the dog 5.

When in the operation of the loom transfer is called for the controller shaft 9 is rocked in a clockwise direction, thus raising the arm 11 from the stud 12 and permitting the spring 16 to advance the feeler arm 14 into feeling position. As the feeler arm moves to shuttle engaging position the dog 5 is raised into the path of the bender 6 upon the lay. As the lay moves forward the end of the feeler arm crosses the path of the shuttle and if the shuttle 26 is improperly positioned therein engages the end or the side of the shuttle so that the further movement of the lay rocks the shuttle feeler upon its pivot 15, into the position illustrated in Fig. 1, thus depressing the dog out of the path of the bender and preventing transfer. The construction and operation of the shuttle feeler thus far described is that of the usual shuttle feeler of the Northrop type of loom.

The essential feature of the present invention consists in providing the shuttle feeler with a shuttle engaging instrumentality adapted to position a latch in the path of the lay so that the shuttle feeler will be actuated through the engagement of the lay with the latch instead of being actuated through the shuttle and its engagement with the end of the feeler, thus providing a more sensitive and efficient construction and avoiding the wear upon the parts above described.

In the preferred embodiment of the invention illustrated herein the shuttle engaging instrumentality comprises a plate 27 pivotally mounted upon a stud 28 at the lower edge of the end of the shuttle feeler arm 14 said plate 27 being provided with a lateral extension 29 which covers the end of the feeler 14 and presents a relatively broad surface for engagement with the shuttle. This lateral extension also serves to engage the end of the feeler arm 14 when the lay in engaging the latch 30 forces the feeler forward, thus providing a very rigid construction. The plate 27 is provided at its opposite end with a downward extension or latch 30 providing a shoulder 31 adapted to engage the lay 7 or a suitable wear plate thereupon.

The shuttle engaging end of the plate 27 may be maintained in extended or shuttle engaging position by any suitable resilient mechanism which will serve also to raise the

latch 30 out of the path of the lay. A convenient mechanism for effecting this result is illustrated herein and comprises a counterweighted member 32 pivotally mounted upon a stud 33 upon the feeler 14 and having an extension or tail 34 provided with an offset end 35 entering a slot 36 in the plate 27. In order to limit the movement of the shuttle engaging plate 27 and its latch 30 the offset end 35 of the tail 34 may be extended sufficiently to enter a slot or preferably a circular aperture 37 in the feeler 14 so that the abutment of the tail 35 with the walls of the aperture will restrict the extent of movement of the plate 27 about the pivot 28.

In the operation of the device the feeler with its pivoted shuttle engaging end is thrust into the shuttle box and if the shuttle is properly positioned within the box the end 29 is maintained in extended position illustrated in Fig. 2 by the action of the counterweight 32 and the latch 30 is retained out of the path of the lay. When however, the shuttle is improperly positioned in the shuttle box the shuttle engaging end 29 of the plate 27 will be rocked about the pivot 28 causing the latch 30 to be positioned in the path of the lay so that as the lay moves forward it will force the shuttle feeler forward through the engagement of the latch and the lay instead of forcing the same forward by reason of the engagement of the end of the latch with the shuttle.

It will be obvious that very little power is required to move the shuttle engaging end of the feeler so that accuracy in operation of the mechanism is insured. Any tendency of the feeler to thrust an improperly positioned shuttle back into the box will be avoided.

In Fig. 5 I have illustrated a modified form of shuttle engaging instrumentality which consists of a plate 38 having a lateral extension or shuttle engaging end 39 overlying the end of the feeler, said plate 38 being provided with two or more parallel slots 40 which are oblique to the longitudinal axis of the plate 38. The plate 38 is mounted through the slots 40 upon studs 41, 42 and is maintained normally in extended position by a spring 43 coiled about the stud 42 and anchored at one end 44 to the plate 38 and at its opposite end having an extension 45 engaging an inclined part 46 of the breast beam of the loom.

The plate 38 is provided with a downward extension or latch 47 presenting a shoulder 48 adapted to engage a lay in the same manner as the latch 30 heretofore described.

It will be understood that the particular embodiments of the invention disclosed herein are illustrative merely and are not restrictive and that the invention may be incorporated in other forms within the meaning and scope of the following claims.

Having described my invention what I

claim as new and desire to secure by Letters Patent is:

1. A shuttle feeler for automatic filling replenishing looms comprising an arm movable toward the lay to feeling position upon call for filling replenishment, a relatively movable member carried thereby and extending beyond and across the end of said arm having means adapted to be positioned in the path of the lay upon engagement of an improperly positioned shuttle whereby the feeler will be actuated by the further movement of the lay through said means to prevent operation of the transferring mechanism.

2. A shuttle feeler for automatic filling replenishing looms comprising an arm movable toward the lay to feeling position upon call for filling replenishment, and an integral instrumentality yieldably mounted upon said arm and extending beyond the end of said arm having an integral extension adapted to be positioned in the path of the lay upon engagement of said instrumentality with an improperly positioned shuttle, whereby the feeler will be actuated by the movement of the lay to prevent operation of the transferring mechanism.

3. A shuttle feeler for automatic filling replenishing looms comprising an arm movable toward the lay to feeling position upon call for filling replenishment and a shuttle engaging plate pivotally mounted upon and extending beyond the end of said arm, having an integral downward extension adapted to be positioned in the path of the lay upon engagement of said plate with an improperly positioned shuttle, whereby the feeler will be actuated by the movement of the lay to prevent operation of the transferring mechanism.

4. A shuttle feeler for automatic filling replenishing looms comprising an arm movable toward the lay to feeling position upon call for filling replenishment, and a shuttle engaging plate yieldably mounted upon said arm having a flange overlying the end of said arm, said plate being provided with a downward extension adapted to be positioned in the path of the lay upon engagement of said plate with an improperly positioned shuttle whereby the feeler will be actuated through the engagement of the latch

with the lay and the flange with the end of the feeler.

5. A shuttle feeler for automatic filling replenishing looms comprising an arm movable toward the lay to feeling position upon call for filling replenishment, a shuttle engaging plate pivotally mounted at the end of said arm having a downward extension or flange adapted to be positioned in the path of the lay, and yieldable means for rocking said plate upon its pivot to cause its end to extend beyond the end of the feeler arm and the latch normally to be removed from the path of the lay, whereby engagement of said plate with an improperly positioned shuttle will position the latch in the path of the lay.

6. A shuttle feeler for automatic filling replenishing looms comprising an arm movable toward the lay to feeling position upon call for filling replenishment, a shuttle engaging plate pivotally mounted at the end of said arm having a downward extension or flange adapted to be positioned in the path of the lay, means including a counterweight for rocking said plate upon its pivot to cause its end to extend beyond the end of the feeler arm and the latch normally to be removed from the path of the lay whereby engagement of said plate with an improperly positioned shuttle will position the latch in the path of the lay.

7. A shuttle feeler for automatic filling replenishing looms comprising an arm movable toward the lay to feeling position upon call for filling replenishment, a shuttle engaging plate pivotally mounted at the end of said arm having a downward extension or flange adapted to be positioned in the path of the lay, a counterweight pivoted upon said feeler arm and having an extension engaging a slot in said plate for rocking said plate upon its pivot to cause its end to extend beyond the end of the feeler arm and the latch normally to be removed from the path of the lay whereby engagement of said plate with an improperly positioned shuttle will position the latch in the path of the lay.

In testimony whereof, I have signed my name to this specification.

ISAAC SNOW.
